(57) **CLAIM**

I claim the ornamental design for a blender, as shown and described.

DESCRIPTION

FIG. 1 is a front perspective view of the blender.
FIG. 2 is an exploded front view thereof, showing how the vessel and base separate.
FIG. 3 is a front view thereof.
FIG. 4 is a rear view thereof.
FIG. 5 is a right side elevation view thereof.
FIG. 6 is a left side elevation view thereof; and,
FIG. 7 is a top plan view thereof.
The broken lines shown depict portions of the blender that form no part of the claimed design.
The bottom of the blender not shown forms no part of the claimed design.
